CLAIM

The ornamental design for a bottle display rack, as shown and described.

DESCRIPTION

FIG. 1 is a perspective view of a bottle display rack showing our new design;

FIG. 2 is a perspective view thereof;

FIG. 3 is a front elevational view thereof;

FIG. 4 is a right side elevational view thereof, the left side being a mirror image of that shown;

FIG. 5 is a top plan view thereof; and,

FIG. 6 is a bottom plan view thereof.

The broken-line disclosure of bottles in the views, and the adjacent racks in shown in FIG. 1 are for illustrative purposes only and form no part of the claimed design.
